UNITED STATES PATENT OFFICE.

AXEL A. STROM, OF AUSTIN, ILLINOIS, ASSIGNOR TO THE STROM MANUFACTURING COMPANY, OF CHICAGO, ILLINOIS.

DESIGN FOR A SWITCH CHAIR OR BRACE.

SPECIFICATION forming part of Design No. 33,200, dated September 11, 1900.

Application filed August 1, 1900. Serial No. 26,593. Term of patent 14 years.

To all whom it may concern:

Be it known that I, AXEL A. STROM, a citizen of the United States, residing at Austin, in the county of Cook and State of Illinois, 5 have invented a certain new and useful Design for a Switch Chair or Brace, of which the following is a specification.

This invention relates to a design for a chair for railway-switches, and has for its object 10 the production of a new and useful design of characteristic and distinguishing appearance which shall be readily distinguishable to the eye from all prior designs for switch chairs or braces.

15 The accompanying drawing shows my design of chair for railway-switches by a perspective view.

The essential feature of my design consists of the chair or brace of the usual general 20 shape having a circular opening in its tail portion surrounded by a series of holes concentric with said opening.

As shown in the drawing, my design consists of the chair composed of the flat and generally-rectangular head A, the neck B, extending therefrom, and the tail portion C, joining the neck at an offset a. In the tail portion C is formed a circular opening D, and about and concentric with the opening in the tail portion are the series of holes E. 25 The circular opening D and the holes E surrounding it give to the design its characteristic and distinguishing appearance. 30

Having thus fully described my invention, what I claim, and desire to secure by Letters 35 Patent, is—

The design for a switch chair or brace, substantially as shown and described.

AXEL A. STROM.
